UNITED STATES PATENT OFFICE

2,516,322

MACHINE FOR SEAMING TUBULAR MEMBERS

Benton D. Jacokes, Jackson, Mich., assignor to
Walker Manufacturing Company of Wisconsin,
Racine, Wis., a corporation of Wisconsin

Original application August 8, 1941, Serial No.
406,032. Divided and this application October
26, 1944, Serial No. 560,504

6 Claims. (Cl. 113—23)

1

The present invention relates to a machine for forming rolled seams on tubular members.

This application is a division of applicant's pending application Serial No. 406,032, filed August 8, 1941, assigned to the assignee of the present application and now abandoned.

It is the present practice in connecting so-called headers, or end closure plates, to the bodies of internal combustion engine exhaust mufflers, to form an interlocking seam by a rolling operation at the joining edges of the muffler and its header.

The object of this invention is to provide an improved form of machine adaptable to perform a rolling operation, such as a seam rolling operation, upon tubular sheet metal members which are non-circular in cross section; more particularly, it is an object of the present invention to provide a machine embodying an improved aligned relationship between a forming roller and the elements which control its feed movements, and to provide such a machine characterized as embodying a forming roller and feeding means therefor including a hydraulic motor and associated means for providing it with a metered flow of actuating hydraulic fluid.

Other objects and advantages of the invention will become apparent from the following specification, the accompanying drawings, and the appended claims.

In the drawings, in which like numerals are used to designate like parts in the several views throughout:

Figure 1 is a fragmentary plan view of a machine constructed to form a rolled seam on tubular sheet metal members which are non-circular in cross section;

Fig. 2 is a fragmentary, sectional view taken on the line 2—2 of Fig. 1;

Fig. 3 is a diagrammatic view of the hydraulic circuit used to operate and control the hydraulic cylinder of the machine;

Fig. 4 is a fragmentary plan view similar to Fig. 1, but on a larger scale, of a portion of the mechanism, parts being broken away, and the cover member for the roller supporting slide being removed;

Fig. 5 is a fragmentary section taken on the line 5—5 of Fig. 4;

Fig. 6 is a fragmentary front elevation of a portion of the machine which carries one of the

2

metal working rollers and is taken on the line 6—6 of Fig. 5, with the workpiece removed to expose the mechanism;

Fig. 7 is an enlarged view showing the form of the parts to be joined prior to the seam rolling operation;

Fig. 8 is a view similar to Fig. 7, illustrating the final stages of the seam rolling operation;

Fig. 9 is a fragmentary view similar to Fig. 7, showing the initial shape of the parts to be joined by a modified or partly flush seam; and

Fig. 10 shows the finished seam produced from the parts illustrated in Fig. 9.

Referring to the drawings, and particularly to Figures 1 and 2, it will be seen that the rolling machine, which in many respects is conventional in form, is constructed upon a bed 10 having a pair of longitudinal V-shaped slideways 11 and 12 running substantially the full length of the bed. The construction and arrangement of the bed and of the machine as a whole are substantially that of an ordinary lathe with the exceptions hereinafter indicated, being provided with a head stock 13 and a tail stock 14, the former fixed to the bed and the latter slideable upon the slideways 11 and 12 in any suitable or conventional manner. The head stock 13 journals a shaft 15 which supports at one end a chuck 16, while a chuck 17 of similar form is supported by a shaft 18 journaled for both rotary and axial sliding movement in the tail stock 14. The machine is provided with an electric motor 20 which drives, by means of a chain 21 and suitable sprockets, a main shaft 22 which is journaled in the bed of the machine and extends the full length of the bed. A gear 23 on the shaft 22 meshes with a gear 24 on the shaft 15 to drive the latter and, therefore, the chuck 16. A gear 26 likewise fixed to the shaft 22 meshes with a gear, not shown, but which is located within the tail stock 14 and splined to the shaft 18, so as to transmit rotary motion to the shaft 18 without preventing axial motion of the shaft 18. A cylinder 27 fixed to the bed of the machine is provided with a piston rod 28 which is operatively connected to the right-hand end of the shaft 18 to effect axial movements of the latter. The connection between the piston rod 28 and the shaft 18 may be of any suitable form, but is preferably designed to permit free relative rotation be-

tween the two without permitting relative axial movement. Any suitable means may be provided to supply fluid or air pressure for operating the piston rod 28.

The structure of the machine so far described is more or less conventional and is, therefore, not shown in detail.

In operation, a workpiece comprising a tubular sheet metal element 30 is held in alignment with the chucks 16 and 17 and fluid is admitted to the cylinder to shift the chuck 17 into work holding position. Thereupon, the motor 20 is started, which effects rotation of the shaft 22 and consequent rotation of the chucks 16 and 17 and work-piece 30.

The present machine is particularly designed to roll a seam on a tubular element 30, which is non-circular in cross section. The particular workpiece illustrated is an oval muffler body 30, to which is to be connected by a rolled seam a sheet metal header 31. This seam may be either of the improved type hereinafter described or any other type of seam, depending upon the construction and form of the roller and the chuck used to support the work. So far as the machine is concerned, the novel features thereof reside in the construction and arrangement of the mechanism for controlling the movement of the roller, which mechanism is best shown in Figures 1, 3, 4, 5, and 6 of the drawings.

In the particular machine illustrated, seams are formed simultaneously at opposite ends of the muffler and, therefore, two roll supporting and operating mechanisms are provided. One of these mechanisms is mounted upon a slide 34 movable longitudinally on the bed of the machine, while the other is mounted upon a similar slide 35. Since the construction and arrangement of the slides 34 and 35 and the mechanism mounted on them are substantially identical, only one need be described. Accordingly, a description will be given of the mechanism on the slide 34, it being understood that the mechanism on slide 35 is similar.

As shown best in Figures 4, 5, and 6, the slide 34 is substantially channel shaped in form, being provided with upstanding side walls 36 and 37 extending transversely of the bed of the machine. Fixedly secured to and bridging across the top of the side walls 36 and 37 is a generally arch shaped cover member 38. The cover member 38, as best shown in Figures 5 and 6, is provided with four stiffening flanges 39, 40, 41 and 42, and the space between the flanges 40 and 41, as well as the space between the flanges 41 and 42, is cut away to form openings 43 and 44, respectively.

The side walls 36 and 37 of the slide 34 are provided with inwardly projecting pads 46 and 47, whose upper edges terminate below the upper edges of the side walls 36 and 37. A secondary slide 50, which is generally U-shaped in form, as best seen in Figure 6, is positioned between the side walls 36 and 37. The upper ends of the legs of the U-shaped secondary slide 50 are provided with horizontally projecting flanges 51, which rest upon wear strips 52 supported upon the top surfaces of the pads 46 and 47. The wear strips 52 slideably support the secondary slide 50 for movement transversely of the bed of the machine with respect to the main slide 34.

At the rear the secondary slide 50 is provided with an end closure wall 54, provided with a pair of rearwardly extending bosses 55 in which is journaled a cam roller 56 adapted to be engaged by cam 57 mounted on a shaft 58 which is jour-

naled between a pair of bosses 59 and 60 carried, respectively, by rearward extensions of the side walls 36 and 37 of the main slide 34.

The cam 57 is driven in synchronism with the chuck 16 by a train of gearing which includes a gear 61 on shaft 58, a gear 62 on a counter-shaft 63, a gear 64 on the counter-shaft 63 and the gear 24 on the shaft 15. In the particular embodiment shown, a seam is to be rolled on a muffler body 30 which is oval in cross section, as best shown in Figure 5, and the cam 57 is so shaped as to oscillate the slide 50 in accordance with the variations in radius of the muffler body 30 at the point of engagement of the roller.

Means are provided for holding the cam roller 56 on slide 50 in engagement with the cam 57, which means comprises a stud 66 threaded into a downwardly projecting boss 67 on the slide 50 and projecting rearwardly through an opening 68 in a portion of the main slide 34. A helical spring 69 surrounds the stud 66 and bears at one end upon the main slide 34 and at the opposite end upon a pair of adjustable lock nuts 70 threaded on the stud.

The metal working roller 72 is journaled on and between the side walls of a U-shaped roller supporting slide 73. The upper ends of the sides of the U-shaped roller supporting slides 73 are provided with lateral projections 74 adapted to overlie the top of the sides of the slide 50, as best shown in Figure 6. Suitable wear strips 76 are provided between the side walls 36 and 37 of the slide 34 and the projecting flanges 74 of the slide 73 to keep the slide 73 in proper alignment as it reciprocates transversely of the bed of the machine with respect to the slides 34 and 50. The slide 73 is provided with a transverse wall 77 rearwardly of the roller 72, and a piston rod 78, which is connected to a piston in a cylinder 79, is fixed to the transverse wall 77 by means of a cap screw 80. The cylinder 79 is positioned between the sides of the slide 50, and its rear end is secured by means of cap screws 82 to the rear wall 54 of the slide 50.

As a result of this arrangement, upon movement of the piston and piston rod relative to the cylinder 79 the roller supporting slide 73 will move relative to the secondary slide 50. A pair of fluid conducting pipes 84 and 85 are connected, respectively, to opposite ends of the cylinder 79, and, as best shown diagrammatically in Figure 3, are connected in a suitable hydraulic circuit, hereinafter described, for operating the cylinder and piston.

Means are provided for limiting the movement of the slide 73 relative to the slide 50 and toward the work. This means comprises a stud 87 which passes freely through a suitable opening in the end wall 54 of slide 50 and is threaded at 88 into the slide 73, as best shown in Figure 5. A pair of lock nuts 89 limits movement of slide 73 toward the work and relative to the slide 50. The adjustment of the nuts 89 is such that upon completion of the seam rolling operation, the stud 87 will relieve the work of the pressure exerted by the hydraulic piston.

The hydraulic cylinder 79 is connected in any suitable or conventional form of hydraulic circuit which will effect a metered flow of fluid under pressure to the line 85 during the seam rolling operation and will effect a quick return movement of the piston upon completion of the rolling operation. Hydraulic control valves and systems for effecting such fluid cycle are old and common, and any suitable type may be used. For example,

as illustrated diagrammatically in Figure 3, the system may include a fluid reservoir 90 connected to a pump 91 by means of a pipe 92, and the discharge line 93 of the pump is connected through a suitable four-way reversing valve 94 alternatively either to the cylinder line 84 or to a line 95 which is connected to the cylinder line 85 through a one-way metering valve 96. A return line 97 from the four-way valve to the reservoir 90 is also provided. Any suitable means such as the operating lever 98 may be provided to shift the spool of the four-way valve 94.

In a circuit of this type, when the control element of valve 94 is in one position, fluid under pressure from the line 93 passes through the four-way valve 94 to the line 95 and thence through the metering valve 96 and the line 85 to the rear end of cylinder 79 to effect the working stroke of the roller 72. The metering valve 96 is of a type which, under this condition of flow, will permit a metered uniform quantity of fluid to pass through the valve and into the rear end of the cylinder 79, thus effecting a uniform rate of feed of the roller 72 independent of the resistance which that roller encounters, the pressure developed by the pump 91 being more than sufficient to overcome any possible resistance the roller will encounter during the seam rolling operation. During the working stroke, the fluid from the front end of cylinder 79 returns freely through line 84, the four-way valve 94, and line 97 to the reservoir 90. Upon completion of the seam rolling operation, valve 94 is reversed, whereupon fluid under pressure from the pump 91 flows through line 93, four-way valve 94, and line 84 to the front end of the cylinder, causing a return of the piston and roller 72. During the return stroke, the fluid in the rear end of cylinder 79 returns through line 85, valve 96, line 95, valve 94, and line 97 to the reservoir 90. The metering valve 96 contains a one-way bypass which will permit a relatively unrestricted return flow of the fluid from line 85 to line 95 to allow a quick return movement of the roller 72.

While the description of the mechanism for controlling movement of the rollers has been limited to that portion of the mechanism mounted on slide 34, it will be understood that the corresponding mechanism mounted on the slide 35 is identical except that the drive gearing for the cam is mounted upon the opposite side of the mechanism and includes a countershaft 63', corresponding to the countershaft 63. The countershaft 63' is driven from a gear mounted within the tail stock 14 and splined on shaft 18 which gear meshes with the gear 64' on the countershaft 63' in the same manner that gear 24 on shaft 15 meshes with gear 64 on shaft 63.

It will be observed that the mechanism for rolling seams on tubular members of non-circular cross section heretofore described is exceedingly compact, simple and light in weight as a result of the fact that all of the roller controlling and supporting elements, including the cam 57, roller 56, the cylinder 79, piston rod 78 and roller 72 are mounted in a direct line. In addition, the slides 50 and 73 are supported at diametrically opposite sides of the axis cylinder 79. As a result of this arrangement, all of the forces exerted are direct compression forces, and there is no possibility of any of the parts cocking out of alignment. In addition, the use of a metered flow of hydraulic fluid for moving the roller 72 on its working stroke greatly simplifies the mechanism and insures that the seam rolling operation will

proceed uniformly independent of any variations in the resistance of the metal to bending. This avoids the formation of wrinkles and otherwise unsatisfactory seams.

- 5 In Figures 7 and 8 is illustrated an improved flush seam and an illustration of the method by which it is formed. In the particular embodiment chosen for illustration, the seam is used to secure a header 31 to a muffler body 30. It will be observed that the header 31 is initially formed by a stamping or sheet metal drawing operation to provide an approximately axial flange having two portions 101 and 102 of slightly different diameters, the outermost portion 102 being of larger diameter than the portion 101 to provide a shoulder between them. Outwardly of the portion 102 the flange is bent outwardly and in an opposite direction at an angle of approximately 45°, forming a conical return portion 103. Prior to the seam rolling operation, the header 31 is fitted within the muffler body 30 with the edge of the muffler body seated within the notch formed between the conical portion 103 and the inner flange portions 101 and 102 of the header. It will be observed that the larger flange portion 102 is of smaller diameter than the internal diameter of the muffler 30, the difference in radius being approximately equal to the thickness of the metal of the muffler header 31.
- 10 30 When the header and muffler are assembled, as shown in Figure 7, they are placed in the seam rolling machine with the header supported upon the chuck 16. It will be understood that the opposite end of the muffler will be similarly supported, as best shown in Figures 1 and 2. The chuck 16 is provided with a stepped extremity adapted to fit the stepped portions 101 and 102 of the header flange. The seam is formed by a rolling operation with a roller 72 of the form indicated in the drawings, in which there is provided on the working face of the roller a projecting annular surface 104 aligned with the flange portion 101.
- 15 40 45 To the left of the annular projection 104 is a working surface 105 of reduced diameter. The difference in radius of the portions 104 and 105 of the roller is equal to the difference in radius of the flange portions 101 and 102.
- 45 50 The seam rolling operation is effected by rotating the chuck 16 with the header 31 and muffler 30 and feeding the roller 72 inwardly. The roller rolls around the periphery of the seam and forces the flange 103, as well as the extremity of the muffler body 30, progressively inwardly until they fit tightly against the inner flange portions 101 and 102 with a corresponding shoulder intermediate the two flange portions. The extremity of the muffler body 30 and the outer flange 103 of the header are, upon completion of the rolling operation, rolled into a stepped relationship of two diameters with an intermediate shoulder between the portions of the different diameters to produce an interlocking seam.
- 55 60 65 70 75 It will be observed that, in addition to forming the seam, the roller during the seam formation effects a general reduction in diameter of the end portion of the muffler 30 by an amount at least equal to the thickness of the metal of the muffler body, with the result that the outermost portion of the finished seam is perfectly flush with the main body 30 of the muffler.
- The seam described is of substantial strength because of the interlocking shoulder, is entirely flush with the main body of the muffler, and has

the advantage that it can be formed in a single, continuous rolling operation by a single roller.

For some purposes where a perfectly flush seam is not required, the flange portion 102 of the header 31 may be made the full internal diameter of the muffler body 30, as shown in Figure 9. In this event, upon completion of the rolling operation the seam will assume the form illustrated in Figure 10. This seam is substantially identical to that illustrated in Figure 8, except that the outermost portion 106 of the seam will project outwardly beyond the main body of the muffler 30 by an amount equal to the thickness of the metal of the header. While this seam is not perfectly flush, its outer projection is far less than that of conventional rolled seams now in use, and to a large extent the handling difficulties encountered with the present seams are eliminated.

It will be understood that various variations in the details of the herein described machine may be indulged in without departing from the spirit of the invention herein disclosed or from the appended claims.

What is claimed is:

1. A machine for performing a forming operation on a sheet metal member which is noncircular but smoothly curved in cross-section, including means to support and rotate the sheet-metal member about an axis extending substantially perpendicularly to said cross-section, a support carried by said machine and movable toward and away from said sheet metal member in a path transverse to said axis, a fluid motor mounted on said support and having a driven element movable with respect to said support in a direction transverse to said axis, a metal working tool on said element and adapted to engage said sheet metal member, means for supplying fluid to said motor at a predetermined rate to effect a correspondingly predetermined rate of movement of said element and tool toward said sheet metal member, and means comprising cam means rotatively journaled on said machine and engageable with said support, for oscillating said support whereby said tool is maintained in operative relation to the sheet metal member as the latter rotates, said cam means having a contour complementary to that of cross-section and having means for driving it in synchronism with the rotation of said sheet metal member.

2. The structure of claim 1 wherein said fluid motor is a hydraulic motor, and said feed means for supplying fluid to said motor includes means for supplying said motor with hydraulic fluid at a predetermined rate.

3. A machine for performing a forming operation on a sheet metal member which is noncircular but smoothly curved in cross-section, including means to support and rotate the sheet-metal member about an axis extending substantially perpendicularly to said cross-section, a support carried by said machine and movable toward and away from said sheet metal member in a path transverse to said axis, a fluid motor mounted on said support and having a driven element movable with respect to said support in a direction transverse to said axis, a metal working tool on said element and adapted to engage said sheet metal member, means for supplying fluid to said motor at a predetermined rate to effect a correspondingly predetermined rate of movement of said element and tool toward said sheet metal member, and means comprising cam means rotatively journaled on said machine and engageable with said support, for oscillating said

support whereby said tool is maintained in operative relation to the sheet metal member as the latter rotates, said cam means having a contour complementary to that of cross-section and having means for driving it in synchronism with the rotation of said sheet metal member, said cam means, motor and tool being in substantial alignment with each other along a line extending substantially normal to said axis.

4. A machine for performing a forming operation on a sheet metal member which is noncircular but smoothly curved in cross-section, including means to support and rotate the sheet metal member about an axis extending substantially perpendicularly to said cross-section, a support carried by said machine and movable toward and away from said sheet metal member in a path transverse to said axis, a fluid-operated piston and cylinder carried by said support and having a driven element movable with respect to said support in a direction transverse to said axis, a metal working tool on said element and adapted to engage said sheet metal member, means for supplying fluid to said cylinder at a predetermined rate to effect a correspondingly predetermined rate of movement of said element and tool toward said member and relative to said support, and means including a cam journaled on said machine and having a contour complementary to that of said cross-section and operated in synchronism with the rotation of said member, for engaging and oscillating said support to maintain said support in fixed relation to the adjacent portion of said sheet metal member whereby the tool is maintained in operative relation to the sheet metal member as the latter rotates.

5. The structure of claim 4 wherein said fluid-operated piston and cylinder are of the hydraulic type and wherein said means for supplying fluid to said cylinder includes means for supplying hydraulic fluid to the same at a predetermined rate.

6. A machine for performing a forming operation on a sheet metal member which is noncircular but smoothly curved in cross-section, including means to support and rotate the sheet metal member about an axis extending substantially perpendicularly to said cross-section, a support carried by said machine and movable toward and away from said sheet metal member in a path transverse to said axis, a fluid-operated piston and cylinder carried by said support and having a driven element movable with respect to said support in a direction transverse to said axis, a metal working tool on said element and adapted to engage said sheet metal member, means for supplying fluid to said cylinder at a predetermined rate to effect a correspondingly predetermined rate of movement of said element and tool toward said member and relative to said support, and means including a cam journaled on said machine and having a contour complementary to that of said cross-section and operated in synchronism with the rotation of said member, for engaging and oscillating said support to maintain said support in fixed relation to the adjacent portion of said sheet metal member whereby the tool is maintained in operative relation to the sheet metal member as the latter rotates, said cam means, the axis of movement of said element and said tool being in substantial alignment with each other along a line extending substantially normal to said axis.
